UNITED STATES PATENT OFFICE

WILLIAM J. BAKER, OF NEWPORT, KENTUCKY

SCREEN MOUNTING FOR REVOLVING WINDOWS

Application filed November 28, 1928. Serial No. 322,533.

This invention relates to an improvement in the mounting of screens for pivot or revolving windows.

Although various means have been devised in the attempt to provide for adequate screening of revolving windows, none have been entirely satisfactory and free from various objections. An object of the present invention is to provide a more efficient screening means wherein the frame of the screen itself does not, at any time, contact with the so called closure or contact member, with which the sash of the revolving type of window is usually provided. Hereinafter a screen and its frame are referred to as a screen.

Another object is to provide a device for the purpose stated, wherein the screens may be easily removed and replaced without requiring adjustment thereof relative to the contact member of the sash.

Another object is to simplify devices of the character above referred to, and to effect a reduction in the cost of manufacturing.

These and other objects are attained by the means described herein and disclosed by the accompanying drawings, in which:

Fig. 1 is a longitudinal cross sectional perspective view showing the relative positions of parts when the window is partly open.

Fig. 2 is a side elevational view showing the frame with the revolving window in partly open position.

Fig. 3 is an isometric view showing one of two identical ends of a contact member forming a detail of the invention.

Fig. 4 is an isometric view of a screen frame support or holder as it appears detached from the window frame.

Fig. 5 is a side elevational view of the window frame and sash showing the device of invention in a modified form.

Fig. 6 is an isometric view showing in detail a part shown in Fig. 5.

The pivot or revolving window structure embodying the present invention comprises,

generally, a window sash 8 pivotally mounted at opposite sides thereof upon opposite sides of a suitable window frame 9. The said opposite sides of the sash are indicated by characters 10 and 11, and those of the frame are indicated by 12 and 13. Upon the window frame 9, adjacent to the pivot line of the sash, are mounted the inner members 26 and 43 of upper and lower screen supports, respectively. The sash 8 has secured thereto the contact members 23 and 45, the former being in constant contact with the member 26, and the latter, with member 43. The members 26 and 43 of the respective screen supports co-operate with the contact members 23 and 45 of the sash to close the space between the upper and lower screens.

The means for pivoting the sash in the frame is as follows; each of the upright sides 12 and 13 of the frame is provided, intermediate the ends thereof, with a rearwardly extending perforate lug 14 adapted to co-operate with similarly disposed perforate lugs 15 extending from the window sash uprights 10 and 11. Short pins 16 passing through the perforations in the pairs of lugs 14-15, and held in place by cotter pins 17 or the like, provide the pivotal mounting for the sash. Said pins are, of course, in axial alignment to provide for a free swinging movement of the sash relative to the frame. Lugs 14 and 15 may be struck from the metal of the sash and frame, or they may be individual members suitably secured thereto, as desired. Movement of the window sash in one direction is limited by abutting flanges 18 formed on the upper and lower sash members 19 and 20, said abutting flanges being adapted to contact the upper and lower rail members 21 and 22 of the frame when the window is closed. Members 19, 20, 21 and 22 are preferably of angle iron shape, by means of which a weather joint may be made, as may be readily appreciated by reference to the disclosure in Fig. 1.

Upon the outer side of the sash, which is the side exposed by Fig. 1, is fixedly secured a longitudinal curved or arcuate contact member 23. Member 23 extends across the sash from sash member 10 to sash member 11 and is secured to said sash members by any suitable means such as screws 24 passing through the contact or closure member and entering threaded bores 25 provided in the sash members 10 and 11. The member 23 is a segmental portion of a longitudinal cylinder the axis of which will coincide, substantially, with the axes of the aligned pivot pins 16, when the contact member 23 is in position upon the sash. In other words, all points on the surface of the contact or closure member 23 are equidistant from the said axis.

The arcuate contact member 23 is adapted to co-operate with the lower transverse member 26 of an upper screen support or holder 27, for providing an insect proof joint as at 28. Lower transverse member 26 is fixedly and permanently secured to the window frame, and is so disposed relative to arcuate member 23 that it rests lightly upon the convex surface of member 23, as shown in Figs. 1 and 2.

The lower transverse member 26 is preferably channel shaped so as to provide a trough or channel 29 in which the framed screen 30 may rest. A similar channel shaped member 31 forms the upper member of the screen holder, and presents a channel 32 for receiving the top portion of the screen 30. It is to be understood that the channel members 26 and 31 are fixedly and permanently secured upon the stationary frame 9, as are the guide strips 33 which preclude lateral movement of the screens in the channels.

It should be apparent from the foregoing that a simple and inexpensive screen mounting has been provided, wherein the lower member 26 of the screen holder serves also as part of a closure means. It is to be noted particularly that screens such as 30 may be very easily removed or replaced. To remove the screen it is necessary only to raise the screen by means of the handles 34, until the lower edge of the screen clears the lip 35 of the screen holder member 26, whereupon the screen may be moved outwardly and downwardly to dis-associate it from the screen holder. Screens from windows of the same size would, of course, be readily interchangeable because the screens themselves carry no locks or latches which would require accurate alignment or adjustment.

The means for mounting the lower screen comprises a channel shaped screen holder 37, similar to holder 26, fixedly secured along the back or inner side 38 of the window frame rail 22, transversely of the frame. The circumferential frame 39 of lower screen 40 is adapted to rest in the channel or trough 41 of holder member 37.

The upper member 42 of the lower screen holder is an inverted J-shaped longitudinal strip of metal curved to provide an arcuate convex contact surface 43. Member 42 is fixedly and permanently secured, by means of rivets or other fastening means, to the rear of the window frame 9, as indicated at 44. Member 42 is disposed transversely of frame 9 in a manner such that the common axis of the pivot pins 16 lies substantially along or adjacent the uppermost surface of member 42. This relationship is clearly disclosed in Fig. 2.

The sash 8 has fixedly mounted thereon a closure or contact member 45 adapted for co-operation with member 42 for providing an insect proof joint. The contact member 45 is provided, preferably, though not essentially, with a complementary concave surface 46 adapted for sliding movement upon convex surface 43 of support member 42. If desired, the contact member 45 may be formed so that only the under surface 47 of the longitudinal lip 48 thereof is in constant contact with the convex surface 43 of member 42. The contact member 45 may be secured to the sash 8 by means of brackets 49 welded or otherwise secured to the ends of the contact member, and screwed to the sash as at 50.

It should be clearly apparent that, as the window is rotated about its pivotal mountings, the contact member 45 will be in constant sliding contact with the screen holder 42. The lower screen 40 may be removed or replaced in exactly the same manner as upper screen 30.

In Fig. 4 is shown the entire lower screen holder including the members 42, 37 and the guide strips 51 which preclude lateral displacement of the screen. It is of advantage, in building up the window structure, to construct the entire screen holder in the manner shown in Fig. 4, and to then secure it to the frame as a complete unit. Spot welded joints are indicated by 52.

Figs. 5 and 6 illustrate a modified form of contact member and its application to the window structure. The combination contact member and screen supporting means 230, of Fig. 6, corresponds to the member 26 of Figs. 1 and 2. Member 260, which is provided with a longitudinal resilient contact strip 261 for resiliently abutting the arcuate contact member 23, may replace the contact member 26 of Figs. 1 and 2. The resilient strip may be secured to the back 262 of member 260 by any suitable means such as by crimping it under a turned edge 263 of member 260. In this form of the device, member 260 does not abut the arcuate contact member 23.

It should be obvious that the joint formed by strip 261 and contact member 23, will be practically impenetrable by dirt and insects.

It is to be understood that various modifications and changes in the structural details

of the device may be made without departing from the spirit and scope of the invention as set forth in the appended claims.

What is claimed is:

- 5 1. The combination with a window frame, of a window sash pivotally mounted relative to the window frame, a closure member associated with the window sash, and a stationary screen frame supporting member disposed for cooperation with said closure member for providing an insect proof joint therebetween. 70
- 10 2. The combination with a window frame, of a window sash pivotally mounted relative to the window frame, an arcuate closure member carried by the window sash, and a screen frame supporting member fixed to the window frame and disposed for cooperation with said closure member for forming with the closure member an insect proof joint. 75
- 15 3. The combination with a window frame, of a window sash pivotally mounted relative to the window frame, a contact member associated with the window sash, a stationary screen frame supporting member disposed in spaced relation with the said contact member, and a cooperative contact member disposed between the said closure member and the screen frame supporting member for closing 80 the space therebetween. 85
- 20 4. The combination with a window frame, of a window sash pivotally mounted relative to the window frame, a closure member associated with the window sash, a stationary screen frame supporting member, and a resilient contact strip cooperating with the closure member and the screen frame supporting member, for providing an insect proof joint therebetween. 90
- 25 5. The combination with a window frame, of a window sash pivotally mounted relative to the window frame, a closure member carried by the window sash, a screen frame supporting member carried by the window frame, and a resilient contact member on the screen frame supporting member for cooperating with the said closure member for providing an insect proof joint therebetween. 95
- 30 6. The combination with a window frame, of a window sash pivotally mounted upon the window frame, contact means disposed on opposite sides of the window sash, and screen frame supporting means disposed for contact with said contact means, for providing an insect proof joint therebetween. 100
- 35 7. The combination with a window frame, of a window sash pivotally mounted upon the window frame, screen frame supporting members disposed on opposite sides of the window sash, and means associated with the sash for contacting the screen frame supporting members to provide an insect proof joint between the contact means and the screen frame supporting members. 105
- 40 8. In a screen mounting means for revolving windows comprising a window frame and a window sash, the combination of means for mounting the window sash for rotation upon the window frame, closure members on opposite sides of the window sash and fixedly secured thereto adjacent to the axis of rotation of the sash, a pair of screen frame supporting members fixedly secured to the outer side of the window frame, a contact means on one of said screen frame supporting members for constantly contacting one of the closure members, and a second pair of screen frame supporting members secured to the inner side of the window frame, one of said second pair of screen frame supporting members being disposed for constant contact with the other of said closure members. 110
- 45 9. In a screen mounting means for revolving windows comprising a window frame and a window sash, the combination of means for mounting the window sash for rotation upon the window frame, closure members on opposite sides of the window sash and fixedly secured thereto adjacent to the axis of rotation of the sash, pairs of parallel screen frame supporting members secured to the window frame transversely thereof, one of each pair of said members being disposed for constant contact with one of the closure members on the sash for providing an insect proof joint between each closure member and its cooperating screen frame supporting member, and a screen insertible between each pair of parallel screen frame supporting members. 115
- 50 10. In a screen mounting means for revolving windows comprising a window frame and a window sash, the combination of means for mounting the window sash for rotation upon the window frame, closure members on opposite sides of the window sash and fixedly secured thereto adjacent to the axis of rotation of the sash, said closure member having a convex outer surface, and a screen holder frame comprising a transverse supporting member mounted on the window frame coextensively with the said closure member and disposed for constant contact with the convex outer 120
- 55 11. The combination with a window frame, of a window sash pivotally supported for rotation relative to the window frame, a curved closure member disposed transversely of the sash adjacent to the axis of rotation of the sash, said closure member having a convex outer surface, and a screen holder frame comprising a transverse supporting member mounted on the window frame coextensively with the said closure member and disposed for constant contact with the convex outer 125
- 60 12. The combination with a window frame, of a window sash pivotally supported for rotation relative to the window frame, a curved closure member disposed transversely of the sash adjacent to the axis of rotation of the sash, said closure member having a convex outer surface, and a screen holder frame comprising a transverse supporting member mounted on the window frame coextensively with the said closure member and disposed for constant contact with the convex outer 130

surface of the closure member for providing an insect proof joint.

12. A combination contact member and screen frame supporting means comprising a J-shaped longitudinal member for disposition transversely of a window frame, the loop portion of said J-shaped member providing a channel for reception of a screen frame, and a co-extensive longitudinal resilient contact member secured to the J-shaped member, the major portion thereof being spaced from the J-shaped member.

13. In testimony whereof, I have hereunto subscribed my name this 23rd day of November, 1928.

WILLIAM J. BAKER.
